CLAIM

The ornamental design for a hand shower, as shown and described.

DESCRIPTION

FIG. 1 is a perspective view of a hand shower;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines shown in the figures are included for the purpose of illustrating portions of the hand shower and form no part of the claimed design.
